UNITED STATES PATENT OFFICE

2,031,882

HEATING OF RADIATORS

Arthur C. Freeman, Norfolk, Va.

Application February 8, 1934, Serial No. 710,365

1 Claim. (Cl. 219—38)

This invention relates to certain new and useful improvements in the heating of radiators.

An object of the invention is to provide a heating unit for radiators of the general character disclosed in Patent No. 1,913,923, granted to Arthur C. Freeman on June 13, 1933 and embodies improvements in the art thereover.

The primary object of the invention is to provide a heating unit for radiators wherein the heating unit is directly inserted into the radiator and to be of the desired length to extend through the desired number of nipples connecting the sections of the radiator at its lower end.

A further object of the invention is to provide a radiator and heating unit combination of the foregoing character wherein the heating unit that is preferably in the form of a cylindrical cartridge and arranged centrally of or eccentric to and spaced from the nipples connecting the radiator sections whereby the annular spaces between the nipples and heating unit permit the flow of water from the end of the radiator opposite the mounting of the heating unit through the lower portions of said annular spaces to enter the zones of the radiator sections adjacent the heating unit while the spaces at the upper sides permit the free flow of hot water and steam.

It is a further object of the invention to provide a heating unit for radiators as described wherein opposite ends of a cartridge carrying the heating element are substantially heat insulated to increase the activity of flow of water in the radiator in a direction toward the heating element and to reduce the temperature of the heating element at its outer end connection with the radiator.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a side elevational view of a radiator equipped with a heating unit in accordance with the present invention;

Figure 2 is a side elevational view of the heating unit detached from the radiator;

Figure 3 is an outer end elevational view of the heating unit;

Figure 4 is an enlarged fragmentary vertical longitudinal sectional view of the radiator with the heating unit set into the lower ends of several sections and showing the annular space between the connecting nipples for the radiator sections and the heating unit; and

Figure 5 is a cross-sectional view taken on line 5—5 of Figure 2.

Referring more in detail to the accompanying drawing, the reference numeral 10 designates a radiator formed of tubular sections 11 having the upper and lower ends thereof configurated for assembly and connection by the nipples 12 as shown in Figure 4 and the tie rods 5 as shown in Figure 1. An elbow fitting 13 is attached to the lower end of one end section 11 of the radiator for the purpose of charging the same with water and said elbow 12 receives a closure cap 14.

The heater 15 that is herein illustrated as an electric resistance element is in the form of a cylindrical cartridge comprising a casing 16 adapted to be inserted through the desired number of connecting nipples 12 for the lower ends of the radiator sections 11 at the end of the radiator 10 opposite the fitting elbow 13 and said heater 15 is adapted to be placed in communication with an electric cord conductor 17 or the like that is to be placed in communication with a source of potential.

The heater 15 has located intermediate the ends of its casing 16 an electric heating unit 18 having a resistance element therein, the inner end of the cartridge casing 16 spaced from the heating unit 18 housing a heat resistant packing 19 while the opposite end of the cartridge casing 16 also receives a heat resistant packing 20, the terminals 21 of the heating unit 18 extending through the packing 20 and exposed at the outer end of the heater 15 for attachment to the conductor element 17. The outer end of the cartridge casing 16 is enlarged and flanged to provide a threaded section 22 and an abutment shoulder 23 engaged with the lower end of the adjacent radiator section 11 as illustrated in Figure 4.

As shown in Figure 4, the heating unit 15 extends through four sections 11 of the radiator 10 but it is to be understood that the heating unit may be of a length to extend through one or more sections of the radiator. Also, it will be observed that the heating unit 15 has the cartridge casing 16 thereof disposed in this showing concentrically of the nipples 12 and spaced therefrom. The radiator 10 may be used as a steam or water heating device and when used as a steam radiator, the water level in the radiator will be substantially on the line L. Water is introduced into the lower ends of the radiator sections 11 through the fitting elbow 13, the screw plug 24 in the end section 11 carrying the elbow 55

being first removed to permit the escape of air from the radiator sections. It will be observed that a minimum of water in the radiator is subjected to the action of the resistance element 18 of the heating unit, opposite ends of the cartridge casing being substantially heat insulated for purposes herein set forth. The water in the lower ends 11a of the radiator sections 11 is converted into steam which rises in the sections carrying the lower ends 11a and flows through the upper ends of all the radiator sections 11, steam condensation being precipitated in the radiator sections spaced from the electric resistance element 18 for reception in the lower ends 11b of the radiator sections spaced from the resistance element 18. The water in the lower ends 11b of the radiator sections is of a temperature considerably lower than the water in the ends 11a of other sections and the cooler water flows through the annular spaces between the connecting nipples and the heating unit to enter the sections 11a. The hot water will flow through the lower portions of the annular spaces between the nipples and heating unit and steam will flow through the upper portions of said spaces and of course, hot water will also flow through the upper portions of said spaces. The radiator is self-contained in that a predetermined quantity of water confined therein is generated into steam and the steam condensation is returned to the body of water for reuse.

To use the radiator as a hot water heater, it is only necessary to increase the supply of water thereto and by connecting the radiator 10 to a water supply system by means of the screw plug 24 and fitting 25, the radiator in addition to providing room heat may be used as a hot water supply heater. The radiator 10 is of a portable character and is to be constructed of a weight permitting ready shifting movements thereof to desired locations and is capable of wide and various uses.

It is to be observed that the cartridge form of the heater provides a hot chamber for heating purposes and a cold chamber to form a reservoir for supplying water to be heated. Also, the cartridge acts as a choke or baffle to restrain the flow of water directly through the lower nipples and thus tends to impede backward current flow. Further, the ends of the cartridge may contain any form of material tending to resist or impede the passage of heat or may even be filled with metal since the outer ends of such metal fillings

will naturally be cooler than the parts adjacent to the heater coil.

In explanation of operation of heater unit, the cartridge is so designed that when heating unit or cartridge is placed in radiator, that portion 5 of radiator which encompasses or includes the actual heating element 18 is a hot portion and that part of radiator outside of the heating unit 18 is a colder portion relatively. As the process of heating continues, the evaporated water in hot 10 section goes upward as steam or as warmer water in circulation and the water which has been evaporated or risen upward by warm current is replaced in the hot chamber by the water from the colder section and this continues as the radiator 15 as a whole gains temperature until eventually the whole radiator establishes a nearly constant uniform temperature balance. The heat curve of temperature flattens out to a level of constant maximum and remains thus flat, meaning 20 that it is functioning with a balance of temperature, showing that the point has been reached when the radiator gives to the surrounding air its constant output of heat from the constant intake of heat from the current supplied to the radiator 25 by the heat element. The radiator is then operating to give off the maximum heat, measured in B. t. u.

While there is herein shown and described the preferred embodiment of the invention, it is nevertheless to be understood that minor changes may be made therein without departing from the spirit and scope of the invention as claimed.

I claim:

In a heater of the character described, a radiator having a plurality of tubular sections connected by ring-like nipples, an electric heater comprising a cylindrical cartridge inserted directly in one end of the lower end of the radiator and disposed to extend through and be laterally 35 spaced from the nipples at least at one side of the cartridge, a heating unit within the cartridge substantially midway the ends thereof and substantially one third the length of the cartridge, the heating unit contacting the wall of the cartridge and a heat resistant packing at the inner 45 end of the cartridge whereby water in the lower ends of the sections spaced from the cartridge will flow through the spaces between the nipples and inner end of the cartridge towards the central portion of the cartridge carrying the resistance means.

ARTHUR C. FREEMAN.
